UNITED STATES PATENT OFFICE

JAN GERARDUS CUPEDO, OF ROTTERDAM, NETHERLANDS

APPARATUS FOR CLEANING BOTTLES AND THE LIKE

Application filed November 2, 1929, Serial No. 404,334, and in the Netherlands November 12, 1928.

The invention relates to an apparatus for cleaning bottles and the like, comprising a number of drums, fixed to a common shaft and rotatably mounted in a receptacle, filled with a cleaning liquid, which drums are separated from each other by partitions, each being provided with a passage, while the bottles, which are supported within the drums by radially placed blades when being conveyed from one drum to the next one, remain in the same radial plane with respect to the drums.

The apparatus is so constructed that the bottles will lie with their sides in contact when passing through the passages, and due to this, the bottles will be successively conveyed from one drum to the other by the pressure of the succeeding bottles.

However, this known construction shows many drawbacks. By applying solid blades not only the apparatus becomes very heavy but moreover the bottles are liable to breakage by the great pressure exerted on the bottles in shifting the same. Apart herefrom it may occur that, if the bottles are not displaced sufficiently, some of them are caught between the rotating drums and the edges of the passages. Finally these kinds of apparatus are only adapted to clean bottles of one single size, but are unsuitable for cleaning different kinds of bottles, such as conical, square, flat bottles, etc.

The object of the invention is to improve the known apparatus and to obtain a light bottle washing machine, by which, owing to its construction, the breakage of the bottles is eliminated and which, moreover, is adapted to clean bottles of the most diverse kinds, without requiring a special adjustment of the apparatus.

According to the invention, each drum is provided with radially outwardly extending comb-shaped members, which at the passage in the partitions between the drums co-operate with fingers, fixed to these partitions, in such a way that the bottles, supported by the comb-shaped members, are forcedly shifted by these fingers from one drum to the next one when moving along the passage in the partition. The comb-shaped members

may be formed as flat arms, provided with horizontal pins, parallel to the rotating shaft.

The accompanying drawings illustrate solely by way of example, an embodiment of the apparatus according to the invention.

Fig. 1 is a perspective view of a drum with some of the comb-shaped members.

Fig. 2 is a part of a sectional view of two drums with the partitions placed between them.

Fig. 3 is a section of the apparatus along the line III—III in Fig. 5.

Fig. 4 is a side view of a supporting member with a bottle resting on it.

Fig. 5 is a schematical front view of the apparatus, the casing being partly broken away.

Each drum 1, which is fixed to the rotating shaft 3 by means of spokes 2, is provided with radially outwardly extending comb-shaped supporting members for the bottles. These supporting members may be formed as flat arms 4, provided with horizontal pins 5. The shape of the arms 4 and the locations of the pins are such that a bottle-shaped space remains between the successive arms.

The drums, arranged in this manner, are fixed side by side to the shaft 3 and are separated from each other by partitions, while the drums are surrounded by guiding strips 7, so that, during rotation of the drums, the bottles are prevented from falling out of the radially directed compartments.

According to the illustrated embodiment, the partitions between the drums consist of concentric circular tubes 8, which are connected to separating-plates 10, near the passage 9.

Fingers 11, adjustable if necessary, are fixed to the lower separating plate 10. These fingers extend into the path of movement of the cooperating drum and extend between the pins 5 fixed to the arms 4. When the bottle, which rests on a supporting member 4, 5, approaches the passage 9 in the partition, it is caught, pushed aside and carried into the next drum by the fingers 11, extending between the pins 5.

This action is repeated, until each bottle

has passed all the drums and is discharged out of the apparatus.

As nothing is left to chance and each bottle is forcedly and in the right position guided 5 from one drum to the next one, it is a matter of course that the apparatus is suitable for cleaning many kinds of bottles.

Bottles of very different diameter may also be treated, without the possibility that the 10 bottles are untimely displaced through a passage to the next drum.

As the supporting pins 5 are placed horizontally the bottles will not rub against the partitions, when rotating with a drum.

15 In order to elucidate the general arrangement of the apparatus, a part of the casing is broken away in Fig. 5.

According to Figure 5 the apparatus consists of three series of four drums, by which 20 each series operates in a separate fluid bath. The series are mutually separated by solid partitions, whereas the drums of each series are separated by partitions composed of tubes 8. These tubes are connected to a water supply-pipe 12 and they are provided with perforations near the highest point, by which it becomes possible to squirt and clean the outside of the bottles.

I claim:—

30 In a bottle washing machine, a receptacle adapted to contain liquid, a shaft rotatably journaled in the receptacle, a drum fixed to and rotatable with the shaft, said drum having circumferential rows of bottle compartments 35 formed by radially outwardly extending arms being fixed to the drum and provided with pins parallel to said shaft for supporting bottles, partitions separating the circumferential rows of compartments, each 40 partition having a passage therein, inclined fingers fixed to each partition adjacent the said passage and extending between the circular paths of the supporting pins for positively discharging the bottles supported by 45 the pins through said passages successively from a compartment of one circumferential row of compartments to a compartment of the next row.

In testimony whereof I affix my signature.

50 JAN GERARDUS CUPÉDO.
